EX

OR D 16,477

DESIGN FOR THE ORNAMENTATION OF BUCKETS.

Design No. 16,477, dated January 19, 1886.

UNITED STATES PATENT OFFICE.

JAMES I. FLANAGEN, OF PHILADELPHIA, PENNSYLVANIA.

DESIGN FOR THE ORNAMENTATION OF BUCKETS.

SPECIFICATION forming part of Design No. 16,477, dated January 19, 1886.

Application filed August 22, 1885. Serial No. 175,414. Term of patent 14 years.

To all whom it may concern:

Be it known that I, JAMES I. FLANAGEN, a citizen of the United States, residing in the city and county of Philadelphia, State of Pennsylvania, have invented and produced a new and original Design for a Bucket, of which the following is a specification, reference being had to the accompanying engraving, forming part thereof.

10 The leading feature of my design for a pail or bucket is an ornamental surface displaying the representation of net work, through which a background is visible.

15 A designates the body of a bucket, and B the surface thereof.

C designates stripes around the body.

D designates the breast of the bucket, and E the foot thereof. The surface B displays the representation of net-work. The meshes are prominent, the remainder of the surface 20 of the body being visible through the meshes as background.

I claim—

A design for a bucket having a surface displaying the representation of net-work, and a 25 background appearing through the meshes, as shown and described.

JAMES I. FLANAGEN.
